UNITED STATES PATENT OFFICE.

JOHN H. BROWN, OF NEW YORK, N. Y.

BOOT.

SPECIFICATION forming part of Letters Patent No. 245,126, dated August 2, 1881.

Application filed April 6, 1881. (No model.)

To all whom it may concern:

Be it known that I, JOHN H. BROWN, a citizen of the United States, residing at New York, in the county and State of New York, have invented new and useful Improvements in Boots, of which the following is a specification.

The object of this invention is to provide the foraminous leg of a boot with a stay which will prevent the leg from puckering. This object I accomplish by the construction of stay illustrated in the accompanying drawings, in which—

Figure 1 represents a perspective view of a boot embodying my invention. Fig. 2 is a detached view of one of the stays.

Similar letters indicate corresponding parts. In the drawings, the letter A designates a boot, the leg B of which is perforated with a large number of holes, so that a ventilation is produced in the interior of said leg, and the boot is fit to be worn in the hot season without inconvenience. By the holes, however, the leg B is weakened and liable to pucker or sag down and to form wrinkles, which, when not prevented, are the source of great inconvenience to the person wearing my boot. To prevent this disadvantage I combine with the foraminous leg of the boot one or more stays, C, which may be made of elastic sheet metal, or of rattan, or any other material suitable for the purpose. If only one such stay is used, I fasten it in the rear of the leg B; but I prefer to use two stays, and to fasten them in the opposite sides of the leg, as shown. In this case I form the stay with a shank, a, which extends down into the quarter of the boot, and with an eye, b, opposite the ankle-bone or astragalus,

so as to prevent inconvenience to the wearer. From the eye b extends the stem c of the stay up to the top of the leg. By these means I am enabled to produce a ventilating boot-leg 40 which will not be liable to pucker or form wrinkles, and which proves to be of great convenience, particularly in the hot season.

It must be remarked that my stay can also be used with common boot-legs, all of which 45 have a tendency to pucker.

What I claim as new, and desire to secure by Letters Patent, is—

1. The combination, with the foraminous leg B of a boot, of an elastic stay consisting of a 50 shank, a, secured in the quarter of the boot, and a stem, c, extending longitudinally along the foraminous leg to or near the top of the same, substantially as described.

2. The combination, with the foraminous leg 55 of a boot, of an elastic stay consisting of a shank, a, an eye, b, and a stem, c, said stay being secured in position and extending longitudinally along the foraminous leg from top to bottom thereof, substantially as described. 60

3. As an improved article of manufacture, a stay for a boot-leg, composed of a shank, a, an eye, b, and a stem, c, substantially as shown and described.

In testimony whereof I have hereunto set my 65 hand and seal in the presence of two subscribing witnesses.

JOHN H. BROWN. [L. S.]
